4 Claims. (Cl. 242—53)

ABSTRACT OF THE DISCLOSURE

A thread guide can be selectively positioned so as to lay down on a reel hanks that are spaced apart axially of the reel. The thread guide is carried by a reciprocable bar which in turn is located by a lever mounted for swinging movement on and relative to the bar. A second reciprocable member is provided with a plurality of spaced notches into which the lever can be selectively inserted so as to cause the thread guide to traverse over any of a plurality of paths spaced apart axially of the reel. Stationary notches are provided which are located between those reciprocable notches; and swinging the lever to position it in the stationary notches, between the formation of hanks, forms a readily locatable ring of thread on the reel between the spaced hanks.

The present invention relates to positioning devices for the thread guides of reeling machines and has for its object the provision of such positioning devices that are adapted to locate accurately on a reel a plurality of spaced hanks. It is an object of this invention to provide such a device in which the hanks are wound on the reel seriatim with a readily locatable ring of thread between adjacent hanks. Other objects and advantages of the present invention will become apparent from a consideration of the following description, taken in connection with the accompanying drawing, in which:

FIG. 1 is a somewhat schematic fragmentary perspective view of apparatus according to the present invention; and

FIG. 2 is a perspective view of a reel carrying hanks produced by the apparatus of FIG. 1.

Referring now to the drawing in greater detail, it will be seen that the reeling machine according to the present invention comprises a lever 101 pivoted through a sleeve 101' on rod 102 carrying a plurality of pig tail thread guides 103. (In FIG. 1 only one of said guides is shown.) Said lever 101 is rotatable about rod 102, but not slidable along the same since sleeve 101' thereof is locked between a pair of bushes 104 integral with rod 102 through screws 105. Parallel to rod 102 there is a bar 106 adapted for a reciprocating movement as shown by arrows, on said bar being secured, through a pair of sleeves 107, a shaped plate 108 on its upper part provided with a plurality of notches (five of them in FIG. 1), respectively indicated at 111, 112, 113, 114 and 115.

Rod 102 is in spaced relation to bar 106 through a plurality of spacer elements 109, each of which is provided with two holes 116 and 117, respectively, through which rod 102 and bar 106 respectively pass.

The device according to the present invention also comprises a plate 120, said plate being arranged parallel to rod 102 on the side opposite bar 106; said plate 120 is provided with a plurality of notches respectively indicated by the numerals 121, 122, 123 and 124. Plate 120 is clamped to the machine frame (not shown) by any known means so that notches 121, 122, 123 and 124 thereof are, when bar 106 is in rest or home position, at the intervening regions of the notches of plate 108. For instance, notch 121 is at the intervening region between notches 111 and

2

112. The size of the notches of the two plates 108 and 120 are the same as are the distances of the various notches from one another on both plates.

Operation of the above described device is as follows: Having arranged lever 101 within notch 111 of plate 108 integral with bar 106, rod 102 owing to such a connection reciprocates together with bar 106 itself.

Assume that at such a position of rod 102 corresponds, bar 106 being stationary, to a position of thread guide 103 substantially corresponding to a plane perpendicular to axle 139 of reel 130 in FIG. 2 and passing through the median portion wherein hank 131 will be formed (FIG. 2).

Due to reciprocating movement of bar 106 and then of rod 102 with thread guide 103, thread 126 from an appropriate source of thread (not shown) thus forms hank 131 on reel 130 when the machine is operating. Hank 131 being completed and leaving the machine in operation, lever 101 is brought into notch 121 of plate 120 for a time necessary for a rotation of the reel, so that thread 126 forms a readily locatable ring between hanks 131 and 132; lever 101 is then brought into notch 112 of plate 108. In said new position of rod 102 and hence of thread guide 103, thread 126 forms hank 132; then, when lever 101 is brought into notch 122, it forms a ring between hanks 132 and 133 and operation goes on similarly forming the various hanks 133, 134 and 135 separated from one another by thread rings as lever 101 is disposed within notches 113, 114 and 115 with short intermediate stops in the notches of plate 120.

Hank 135 being completed, it is possible to interpose a sheet of paper or a divider on each of hanks 131, 132, 133, 134 and 135 and, by repeating the above described movements of lever 101, to superimpose another hank on each of such above cited hanks. On repeating continuously the described cycle with a thread coming out from each of the thread guides, it is thus possible to form a plurality of side-by-side hanks on the reel, each of which can be in turn comprised of two or more hanks superimposed and separated from one another by means of a sheet of paper or a divider.

What is claimed is:

1. A positioning device for the thread guide of a reeling machine, comprising a first member reciprocable in a first direction, a thread guide carried by said first member, a lever mounted for swinging movement on and relative to said first member, a second member reciprocable in a second direction parallel to said first direction, said second member having a plurality of notches thereon spaced apart in a direction parallel to said first and second directions, said first member being reciprocable relative to said second member whereby said lever may be selectively swung into and out of any of said notches, so that upon engagement of said lever in one of said notches and reciprocation of said second member, said first member and said thread guide reciprocate with said second member to cause thread passing through said thread guide to traverse during the formation of a first hank of thread on a reel, while upon disengagement of said lever from said one notch and movement of said first member in said first direction relative to said second member and reengagement of said lever in a different notch and continued reciprocation of said second member, the thread passing through the thread guide is caused to traverse during the formation of a second hank at a location spaced axially from said first hank.

2. A positioning device as claimed in claim 1, and a stationary member having a plurality of notches therein corresponding in location to the spaces between the notches carried by said second member, said lever being selectively positionable in said stationary notches to form on the

reel readily locatable rings of thread between said first and second hanks.

3. A positioning device as claimed in claim 2, the spaces between said reciprocable notches and said stationary notches all being equal.

4. A positioning device as claimed in claim 1, the spaces between said notches being equal.
